UNITED STATES PATENT OFFICE.

CARL Z. ALEXANDER AND EARL S. ALEXANDER, OF NEWARK, NEW JERSEY, AS
SIGNORS, BY MESNE ASSIGNMENTS, TO EDWIN C. SEWARD, OF JERSEY CITY, NEW
JERSEY.

SECTIONAL STEAM BOILER.

Application filed October 5, 1921. Serial No. 305,674.

This invention relates especially to sectional boilers for steam heating, etc., of the general type covered by the Alexander Patent No. 1,240,804, of September 25, 1917, and
5 in which each regular or body section of the boiler at least comprises one or more geyser tubes formed or cast in connection therewith and exposed to the heat of the fire and preferably having bent or depending water legs
10 which may more or less enclose the fire box at the top to guide the hot gases through the sections in the desired way. These geyser tubes, which preferably are of sufficiently restricted area to give good water circulating
15 or lifting action, communicate with the water spaces or water jackets of the fire box portions in each section; and when the boiler is in operation sufficient steam is generated in these geyser tubes and connected
20 water legs to automatically carry the water up to the steam chambers or supplemental heating surfaces in the upper part of the boiler above the normal water line. Two or more such steam chambers may, if desired,
25 be cast together or otherwise joined to form a unitary steam chamber portion of the boiler section and may be connected to the fire box portion by the geyser tube or connection which may advantageously be arranged adjacent the centre of the section, and also, if desired, by supplementary geyser devices or water supply connections of which one or more may be arranged at other parts of the section. The steam chambers may
30 be formed with laterally sloping surfaces and with transverse ribs or projections to form one or more tortuous or staggered water channels over which the water from the geyser tube devices normally flows in thin
35 sheets or streams while further evaporation takes place. The boiler may be built up of any desired number of these vertical or other sections which may be four to eight inches wide more or less and connected together
40 by the usual nipple connections used in such work. At the ends of these regular or body sections the boiler front and back may be secured in any suitable way and may in some cases be given a special water jacketed
45 form so as to guide the hot flue gases as they move in zigzag paths over and between the steam chambers. In some cases, however, it is more desirable to have special front and rear sections formed with specially

designed steam chambers or portions which 55 provide these smoke circulating passages, although this is not, of course, necessary in all cases.

In the accompanying drawing showing in a somewhat diagrammatic way an illustrative embodiment of this invention,

Fig. 1 is a vertical section through the boiler taken substantially along the line 1—1 of Fig. 2.

Fig. 2 is a partial horizontal section taken 65 along the lines 2—2 of Fig. 3 to show the different steam chambers.

Fig. 3 is a longitudinal vertical sectional view taken as to the end section at the left-hand of Figure 3 upon line 3—3 of Fig. 70 1, as to the next section toward the right-hand upon line 3^a—3 of Fig. 1, and as to the remaining three sections at the right-hand side of Fig. 3 upon the line 3^b—3 of Fig. 1, 75 the combining of these different sections in a single figure enabling them to be directly compared and the construction better understood.

Fig. 4 is a partial horizontal sectional view taken along the line 4—4 of Fig. 1. 80

The boiler may be formed with any desired number of replaceable connected sections and, of course, more sections may be added to the boiler from time to time to increase its capacity. Each of the regular or body sections may have the construction shown in Fig. 1 and comprise an ash pit portion 1 over which a grate 2 of any desired form and construction may be arranged. Above the grate the fire box portion is arranged and bolted or otherwise secured thereto when the boiler is assembled, the sides being preferably, though not necessarily, formed of cast iron or steel and comprising the outer wall 4 having a flaring water space or drum 15 adjacent its lower end where the section nipples 14 are arranged to disengageably connect the adjacent sections. The inner wall 11 of this fire box portion may in some cases be carried or flared inward somewhat adjacent the top to form a somewhat enlarged steam space 10 and this inner wall preferably has an opening at about the point 13 so as to supply water freely to the geyser tube devices which have depending water leg channels 12 extending down adjacent or forming the central part of the inner surface of these fire

- box portions of the section. As indicated in Figs. 1 and 4, these substantially vertical water leg channels 12 may extend part way across each fire box portion on one or both sides of the same and at their upper ends they may communicate with the bent water legs or portions 40 connecting these side members and which are preferably flared out considerably so that, if desired, they may 10 form a perforated top extending throughout the fire box of the furnace and with suitable dust passages, 54, 55 extending entirely or partly across the fire box between these water legs to allow the accumulated dust to 15 drop therethrough into the fire box and for this reason the upper surfaces of these water legs are preferably inclined or arched somewhat to further facilitate this discharge of dust.
- 20 The steam chamber portion of the section preferably comprises two or more superimposed steam chambers which are located above the normal water level of the boiler and, as illustrated in Fig. 1, the two steam 25 chambers 7, 8 may be cast in one piece so as to form a convenient unit for manufacture, handling and transportation. These steam chambers are supplied with water by the automatic water supply or geyser devices connected with the fire box portion of the section and a substantially central water supply may be furnished by the geyser tube or connection 17 which may be forced or screwed into the upper end of the geyser chamber 16 with which the water legs 40 communicate, while the upper end 18 of this geyser tube may have a similar screw connection with a flange in the lower part of the upper steam chamber 7. For the convenient assembly of these parts a screw plug such as 51 may be arranged at the top of this steam chamber so that by unscrewing it the geyser tube connector 17 may be inserted and screwed home so as to also connect and hold together the steam chamber and fire box portion of each of the boiler sections. This upper steam chamber may have its lower surface slope outwardly from the centre thereof and may, as indicated in 40 Fig. 2, have a series of transversely arranged ribs or portions 19, 20 extending part way across the same so that the water automatically supplied to this upper steam chamber through geyser tube 18, as indicated by the 45 arrows in Fig. 2 flows through the staggered water channels on both sides of the chamber until it finally passes down through the drain connections 23 to the lower steam chamber 8 below. This lower steam chamber has its bottom inwardly sloping and has similar transverse ribs or portions 27, 28 so that, as indicated by the arrows in Fig. 2, the water is guided in a staggered or tortuous water channel over the lower heated 50 surface of this steam chamber in which evaporation takes place to a considerable extent before the remaining water passes into the opening 26 communicating with the return passage 24 and thence passes through the passage 25 to the lower water spaces of 70 the boiler section. In some cases it is desirable to have cleaning out plugs or openings arranged in these steam chambers substantially in line with or communicating with the heating surfaces thereof and such 75 removable screw plugs as 52 may be arranged at any convenient or suitable point for this purpose. By unscrewing these plugs cleaning devices can be inserted into the steam chambers to clean the water passages 80 therein and detach any incrustation or scale from time to time where hard water is being handled.
- 85 In addition to the central automatic water supply to the steam chambers from the geyser tube mentioned, supplementary geyser devices or water supply connections may be arranged between the fire box portion and the steam chambers if desired and for this 90 purpose one or more lateral nipple connections 22 may be forced into the tapered sockets in the steam space 10 and the bottom of the upper steam chamber 7 so as to make the usual force fit connection between these 95 parts when each boiler section is assembled. These parts may, of course, be further tightened and held together in suitable ways as by the use of connector bolts 37 extending through flanges on the fire box portion and steam chamber portion of each section so 100 that, for example, the push nipple water supply connections 22 may be put in place and then these connector bolts tightened at least to a considerable extent after which the screw connection geyser tube 17 may be 105 inserted and screwed home to fully connect these co-operating portions of the boiler section. In assembling the sections the section nipples 14 are inserted at the bottom of each fire box portion and at one or more parts of 110 the steam chamber portion of each section and screwed or forced together to form a tight joint in the usual way. Side plates such as 6 may be used on one or both sides of the steam chamber portion and some or 115 all of the sections may have connected thereto the steam pipes 21 supplying steam to the house heating system or other places of use while the return pipes may in some cases have a float chamber such as 35 connected by the T 34 and nipple 33 screwed into the projecting flange 32 communicating with a steam space of one or all of the sections while the water connection pipe 36 extends down to one of the water spaces of 120 the boiler. As is seen in Fig. 3 these nipple connections 33 and flanges 32 may be arranged at one side of the lateral water supply connections 22 which may be arranged 125 in the central plane of each section if de-
- 130

sired. Preferably the lower steam chamber may be formed with an inner circular wall 39 of rather large diameter so as to form an annular smoke passage 29 around the 5 geyser tube which contributes toward the heating of this tube and promotes the water circulation therethrough.

The fire in the grate 2 heats the adjacent walls of the fire box portions of the different 10 furnace sections and by radiation highly heats the water legs of the geyser tube devices above, which is of course of considerable importance in starting the fire since these relatively small area water legs are 15 in the direct path of the flames so as to be quickly heated when the fire is started and promptly supply water to the steam chambers above. Under normal operating conditions the smoke and hot gases from the fire 20 pass up toward the top of the fire box and while they pass between the water legs to some extent they mainly move backward as indicated by the dotted arrows in Fig. 3 and then pass up around the back water legs 25 50 which may, as indicated, be given a special narrow form in the rear section of the furnace so as to leave an ample smoke passage behind these water legs 50 and allow the smoke and hot gases to reach the lower 30 smoke flue 9 above the water legs and below the lower steam chambers 8. The full line arrows show the direction of movement of these hot gases toward the front of the furnace where they may pass up in front of 35 a special lower steam chamber 48 of narrow construction as indicated so that these gases can move up above the lower steam chambers and then pass backward as indicated by the arrows through the upper smoke passages 40 43 and supply heat to the upper steam chambers 7 before the gases pass into the smoke box or breeching 58 communicating with the chimney. If desired, special back boiler sections, such as 41, of water jacket construction 45 may be used at the rear of the special boiler sections described and connected therewith by the bottom nipples 14 such as connect the special steam chamber sections. Similarly a special furnace front 42 may be provided of generally similar water 50 jacket construction, also connected to the other sections and having suitable cleaning and firing doors such as 38.

This invention has been described in connection with a number of illustrative embodiments, forms, proportions, parts, arrangements, materials, constructions and methods of manufacture and use, to the details of which disclosure this invention is 55 not of course to be limited, since what is claimed as new and what is desired to be secured by Letters Patent is set forth in the appended claims:

1. A boiler comprising a series of detachably connected vertical sections each com-

prising a fire box portion of water jacket construction having depending water legs of substantially the same width as the width of the fire box portion and connecting the upper parts thereof, a steam chamber portion co-operating with and connected to each fire box portion and comprising a plurality of communicating superimposed steam chambers each having elongated water channels, a substantially vertical geyser tube 70 connecting each of the steam chamber portions with the water legs in the corresponding section and a lateral supplemental water supply connection between said upper steam chamber and the upper part of the 75 said fire box portion to supply additional water to the steam chambers under forced firing conditions, there being a series of smoke flues adjacent said fire box water legs and below each of the steam chambers to supply heat thereto from the hot furnace gases, and furnace front and back members secured to 80 said sections and formed with cleaning and firing doors and smoke box connections.

2. A boiler comprising a series of connected vertical sections each comprising a fire box portion of water jacket construction having depending water legs connecting the upper parts thereof, a steam chamber portion co-operating with and connected to each fire 90 box portion and comprising a plurality of communicating superimposed steam chambers each having elongated water channels, a substantially vertical geyser tube 95 connecting each of the steam chamber portions with the water legs in the corresponding section there being a series of smoke flues adjacent said fire box water legs and below each of the steam chambers to supply heat thereto from the hot furnace gases.

3. A boiler comprising a series of connected vertical sections each comprising a fire box portion of water jacket construction having depending water legs, a steam chamber portion co-operating with and connected to each fire box portion and comprising evaporating surfaces above the normal water level in the section, a substantially vertical geyser tube connecting each of the steam chamber portions with the water legs 100 in the corresponding section, there being smoke flues adjacent said fire box water legs.

4. A boiler comprising a series of vertical sections each comprising a fire box portion of water jacket construction having depending water legs, connecting the sides thereof, a steam chamber portion co-operating with each fire box portion and comprising a plurality of communicating superimposed steam chambers, a geyser tube detachably connecting each of the steam chamber portions with the water legs in the corresponding section and a supplemental water supply connection between said steam chamber portion and the upper part of the said fire box 115 120 125 130

portion to supply additional water to the steam chambers under forced firing conditions, there being a series of smoke flues above said fire box water legs and below each of the steam chambers to supply heat to said steam chamber portions from the hot furnace gases, and water jacket furnace front and back members secured to said sections and formed with cleaning and firing doors.

5. A boiler comprising a series of vertical sections each comprising a fire box portion of water jacket construction having depending water legs connecting the sides thereof, a steam chamber portion co-operating with each fire box portion and comprising evaporating surfaces above the normal water level in the section, a geyser tube connecting each of the steam chamber portions with the water legs in the corresponding section, there being a series of smoke flues above said fire box water legs and below each of the steam chambers to supply heat to said steam chamber portions from the hot furnace gases.

6. A boiler comprising a series of connected vertical sections each comprising a fire box portion of water jacket construction having water legs extending adjacent the top of the fire box portion and of substantially the same width as the width thereof, a steam chamber portion co-operating with and connected to each fire box portion and comprising tortuous water channels, a geyser tube connecting each of the steam chamber portions with the water legs in the corresponding section, there being a series of smoke flues above said fire box water legs and below said steam chamber portions to supply heat thereto from the hot furnace gases, the rear boiler section having narrow water legs above the fire box to allow the smoke gases to pass behind the same and the front section having a narrowed steam chamber portion to permit the passage of smoke gases in front thereof and water jacket furnace front and back members secured to said sections and formed with cleaning and firing doors.

7. A boiler comprising a series of connected vertical sections each comprising a fire box portion having water legs extending adjacent the top of the fire box portion and of substantially the same width as the width thereof, a steam chamber portion co-operating with and connected to each fire box portion and comprising evaporating surfaces above the normal water level in the section, a geyser tube connecting one of the steam chamber portions with the water legs in the corresponding section, there being a series of smoke flues above said fire box water legs and below said steam chamber portions to supply heat thereto from the hot furnace gases, the rear boiler section having narrow water legs above the fire box to allow the

smoke gases to pass behind the same and the front section having a narrowed steam chamber portion to permit the passage of smoke gases in front thereof and water jacket furnace front and back members secured to said sections.

8. A boiler comprising a series of connected vertical sections each comprising a fire box portion having water legs extending adjacent the top of the fire box portion and of substantially the same width as the width thereof, a steam chamber portion co-operating with and connected to each fire box portion and comprising evaporating surfaces above the normal water level in the section, a geyser tube connecting one of the steam chamber portions with the water legs in the corresponding section, there being smoke flues above said fire box water legs and below said steam chamber portions to supply heat thereto from the hot furnace gases, the rear boiler section having a vertical smoke passage above the fire box to allow the smoke gases to pass behind the same and the front section having a vertical smoke passage to permit the passage of smoke gases in front thereof and furnace front and back members secured to said sections.

9. A boiler comprising a series of detachable vertical sections each comprising a fire box portion of water jacket construction having adjacent each side of the fire box a relatively narrow water leg channel communicating with the water space at the lower part of this fire box portion, bent depending water legs connecting the upper parts of said fire box portion and communicating with said water leg channels, a steam chamber portion co-operating with and connected to each fire box portion and comprising a plurality of communicating steam chambers each having tortuous water channels, a substantially vertical geyser tube detachably connecting each of the upper steam chambers with the water legs in the corresponding section, there being a series of smoke flues above said fire box water legs and below each of the steam chambers to supply heat thereto from the hot furnace gases.

10. A boiler comprising a series of detachable vertical sections each comprising a fire box portion of water jacket construction having adjacent each side of the fire box a relatively narrow water leg channel communicating with the water space at the lower part of this fire box portion, bent depending water legs connecting the upper parts of said fire box portion and communicating with said water leg channels, a steam chamber portion co-operating with and connected to each fire box portion and comprising tortuous water channels, a geyser tube connecting each of the upper steam chambers with the water legs in the corre-

- sponding section, there being a series of smoke flues above said fire box water legs and below the steam chambers to supply heat thereto from the hot furnace gases.
- 5 11. A boiler comprising a series of vertical cast metal sections each comprising a fire box portion of water jacket construction having adjacent each side of the fire box a relatively narrow cast-in water leg
- 10 channel communicating with the water space at the lower part of this fire box portion, integral bent depending relatively wide water legs connecting the upper parts of said fire box portion and communicating
- 15 with said water leg channels, a steam chamber portion co-operating with and connected to each fire box portion and comprising a plurality of staggered water channels, a geyser tube connection detachably connect-
- 20 ing each of the upper steam chambers with the water legs in the corresponding section and a lateral supplemental water supply connection between said upper steam chamber and the upper part of the said fire box
- 25 portion to supply additional water to the steam chambers under forced firing conditions, there being a series of smoke flues above said fire box water legs and below the steam chambers to supply heat thereto from
- 30 the hot furnace gases.
12. A boiler comprising a series of vertical cast metal sections each comprising a fire box portion of water jacket construction having adjacent each side of the fire box a water leg channel communicating with the water space at the lower part of this fire box portion, integral bent relatively wide water legs connecting the upper parts of said fire box portion and communicating with
- 35 said water leg channels, a steam chamber portion co-operating with and connected to each fire box portion and comprising a plurality of staggered water channels, a geyser tube connection detachably connecting each
- 40 of the upper steam chambers with the water legs in the corresponding section there being a series of smoke flues above said fire box water legs and below the steam chambers to supply heat thereto from the hot
- 45 furnace gases.
- 50 13. A boiler comprising a series of cast iron vertical sections each comprising a fire box portion of water jacket construction having connecting each side of the fire box portion water legs communicating with the water space at a lower part of the fire box portion, said water legs forming a largely
- closed top across the upper parts of said fire box portion to direct the smoke gases along beneath the same, an integral cast iron steam chamber portion co-operating with and connected to each fire box portion and comprising a plurality of communicating superimposed steam chambers each having tortuous water channels, a substantially centrally located vertical geyser tube connection detachably connecting each of the upper steam chambers with the water legs in the corresponding section, there being a series of smoke flues above said fire box water legs and below each of the steam chambers to supply heat thereto from the hot furnace gases.
- 55 14. A boiler comprising a series of cast iron vertical sections each comprising a fire box portion of water jacket construction having connecting each side of the fire box portion water legs communicating with the water space at a lower port of the fire box portion, said water legs forming a top across
- 60 the upper parts of said fire box portion to direct the smoke gases along beneath the same, a cast iron steam chamber portion co-operating with and connected to each fire box portion and comprising a plurality of
- 65 communicating superimposed steam chambers each having water channels, a geyser tube connection detachably connecting each of the upper steam chambers with the water legs in the corresponding section, there being a series of smoke flues above said fire box water legs and below the steam chambers to supply heat thereto from the hot
- 70 furnace gases.
- 75 15. A boiler comprising a series of cast sections each comprising a fire box portion of water jacket construction having water spaces connecting each side of the fire box portion and forming a partly closed top
- 80 across the upper parts of said fire box portion to direct the smoke gases along beneath the same, an integral cast steam chamber portion co-operating with and connected to each fire box portion and comprising a plurality of communicating superimposed steam chambers, a vertical geyser tube connection connecting each of the steam chamber portions with the water spaces in the
- 85 corresponding section, there being a smoke flue above said fire box water spaces and below the steam chambers to supply heat thereto from the hot furnace gases.
